UNITED STATES PATENT OFFICE

THOMAS B. BUTLER, OF NORWALK, CONNECTICUT.

IMPROVEMENT IN MACHINERY FOR FORMING BATS FOR FELT CLOTH.

Specification forming part of Letters Patent No. 33,426, dated October 8, 1861.

To all whom it may concern:

Be it known that I, THOMAS B. BUTLER, of Norwalk, in the county of Fairfield, State of Connecticut, have invented an improvement in the mode of crossing the slivers of weft or filling at right angles or any other desired angle in forming bats for felt cloth and other purposes; and I do declare that the following is a full and exact description thereof, reference being had to the accompanying drawings, and the letters of reference marked thereon.

In its nature my invention is an improvement on the invention of Levi Van Hoesen, Jr., patented June 27, 1829; and in principle it consists in giving to the end of one of his side aprons and the roll around which it revolves a traversing alternate motion entirely across the main or warp apron, whereby the weft is deposited from a single apron entirely across the warp, and, further, in giving to the same end of the apron and roll a lateral motion parallel with the main apron while the weft is being deposited and at such a relative and adjusted speed as may be necessary to deposit the weft at a right or any other desired angle, dispensing with one of his machines and aprons and the lateral vibratory motion of his main or warp apron.

In its construction my improvement consists in attaching the roll at the end of the side apron to a movable frame or carriage running on tracks over and parallel with the main apron and geared to move with that apron while the weft is being deposited on the warp and at such relative speed as the desired angle at which the weft is to be laid may require, and in arranging upon each end of the roll a pinion or small gear and upon the sides of the movable frame or carriage a double rack, into which the pinion meshes, whereby and by the revolution of the roll by the revolving apron an alternate traverse movement of the roll and apron across the main or warp apron is effected for the deposition of the weft; but to enable others skilled in the art to make and use my invention, I will proceed to describe so much of the original invention as I retain and my improvement arranged thereon, referring to the drawings, and also the mode in which the whole is operated, distinguishing thereafter what I claim as new.

A' A are the doffers of the two carding-machines, placed at right angles and of such width as may be required. A proper width for making cloth one and one-half yard wide is from eight to nine feet.

B B' are apron-drums, on which an endless apron C C revolves. The bat is formed on this apron, the warp being received thereon from A' and the weft from the endless apron b b b b, hereinafter described.

D D D is a table made of thin boards held together by battens and supported at the corners by stands from the floor. This may be made adjustable by any of the devices in use, so that the distance between the table and the traversing roll j may be increased or diminished at pleasure. The apron C C slides over it and is supported by it in a horizontal plane, so that the apron b b b may at all times be equidistant from the apron C C while it is depositing the weft across it.

E E E E is a movable frame or carriage composed of four perpendicular posts connected at the lower part each way by cross-girts E' E' and one way at the top by girts E² E². This frame rests on the revolving rollers F F on track-rails G G G for the purpose of easy motion back and forth. H' H are pinions fixed on each end of a cross-shaft J, which mesh into racks I I on each side of the frame or carriage for the purpose of moving the carriage back and forth during the operation of the machine.

K is a gear revolving on a stud fixed in a stand attached to the floor and meshing into the pinion H for the purpose of moving the carriage forward. Motion is given to this gear by a belt o from the apron-drum B', running around a pulley attached to the outer side of the gear. This gear has a part of its teeth cut out to permit the carriage to be thrown back without stopping the motion of the gear.

L is another gear, also meshing into the pinion H' for the purpose of throwing the carriage back when the gear K presents its toothless surface to the pinion H'. The gear L is operated by the spring M, one end of which is attached to a block on the floor and the other by a connecting-arm N to the gear L. The operation of the gear L may also be aided by putting weights at proper points upon its arms or periphery. The only object sought to be attained by this gear is the re-

turn of the carriage to its starting-point during the time that the gear K ceases to mesh into the pinion H.

a a is a drum or roll, which is connected by gear or band with the doffer A of the side carding-machine to move the side apron b b b b. The apron b b b b revolves around another small roll j, the journals of which pass through a bearing e. This apron also passes over two rolls c c, whose journals run in bearings which slide up and down in the slot d d, moved by the cords i for the purpose of giving tension to the apron.

g g are double racks, in which the pinions f on each end of the roll j mesh, and which traverse the roll and side apron across the main apron as the roll is made to revolve. In the center of these double racks is a plate h h, under and above which the end of the journal of the roll j moves alternately. This plate serves to keep the pinion f in gear. A different bearing may be substituted for the movable bearing e on a working-machine made in a different manner and as shown in Fig. 2. In that figure, which is a side view of one of the bearings and track-plates, a' is a double track-plate, which may be firmly bolted onto the inside of the carriage, acting also as a cross-girt in place of the inside slotted wooden one shown on the drawings, Fig. 1. The edges of the track-plate should be beveled off to a narrow or V surface in the center.

e² e² is the bearing, which is fixed between the track-plates by friction-rolls x at its angles. These rolls x are channeled on their periphery to match the beveled edges of the track-plate. The bearing should be of sufficient thickness to possess strength, but unnecessary weight should be avoided. Between these bearings are arranged the apron-roll j, two small rolls d² d², for supporting and guiding the apron, a small roll c², resting against the apron to retain the weft in its place, and a clipper k, made with blades like those used upon burring-cylinders to knock the weft down if it should adhere to the apron and be carried back instead of running off. The several rolls resting in this bearing will all receive their motion from the apron, as shown, except the clipper, and that may be moved by a band from the roll j. The surface speed of the clipper k should be about four times that of the apron. The openings in these bearings for the journals of the apron-roll j should be somewhat slotted perpendicularly to enable the end of the journal to slide alternately over and under the plate h in the center of the double rack g g. (See Fig. 1.)

Motion is communicated to all parts of the machinery from the doffers of the carding-machines. For the bands which connect the doffers with the apron-drums, as represented in the drawings, gearing should be substituted in the working-machines. The traveling carriage will require to move about seven feet during the deposition of each sliver, and

the center of the carriage should be placed at the time its movement commences about three and a half feet from the center of the side carding-machine, or rather from a line drawn from the center of the side carding-machine. It will then travel during its movements three and a half feet each way from that line. In order that the apron may run without difficulty, the side carding-machine should be placed at considerable distance from the carriage. The length of the apron is in itself no material objection. The side carding-machines may be placed in an upper story or at any desired distance on the same floor; or the apron may be run up perpendicularly from the carding-machine and over rolls suspended from the ceiling, which rolls can be alternately elevated and depressed by positive motion communicated by the doffer of the carding-machine by well-understood devices. If any difficulty arises from the angular working of the apron, it may be further obviated by attaching thin and narrow strips of band-iron to the under side of the apron to keep it stretched laterally and putting suitable flanges on the ends of the rolls.

Little needs to be added to show the mode of operation of the machine. Motion being communicated to the carding-machines, the apron-drums and aprons are simultaneously set in motion, and one receives the warp and the other the weft as they are combed in the usual manner from the doffers. As the drum B' revolves it also communicates motion to the gear K, which being properly set puts in motion the carriage E E E E, and it moves at the desired speed with the apron. The speed of the carriage is or may be regulated by the size of the pulleys on B' or K. If it is desired to lay the slivers precisely at right angles, the relative speed of the carriage and main apron should be the same. When an angle in either direction is desired, a different-sized pulley will give a more or less rapid relative speed and the weft will be laid at a corresponding angle. The side machine may be worked with or without a grooved doffer and the weft laid in separate sheets or continuously. A grooved doffer is made by grooving out longitudinally a space—say four inches—of the circumference of the doffer and leaving that without card-clothing or with the teeth knocked down into the groove, so as to take no wool from the main cylinder, and the weft will be formed in separate sheets. If run off continuously, the sudden return of the carriage when the toothless portion of the gear K is presented to the pinion H' will separate the weft. This will require less care in adjusting the machines, and will probably prove the best in practice. The weft is carried upon the apron b b b b by the revolution of the apron and the traverse of the apron-roll j and run off each way upon the warp as the roll and apron pass alternately back and forth across the carriage, the apron b b b b acting as a band upon the roll j. In this as

in all other cases where a bat is formed upon an endless apron a slat apron to revolve under the main one is required to support the bat when passing beneath; but they are so simple and common as not to require description.

I do not claim the carding-machines, nor the placing them at right angles or in combination, nor the arrangement or operation of the apron-drums, rolls, or aprons for receiving, conveying, or depositing the wool, for these were all described in the patent of the said Levi Van Hoesen; but

I do claim—

1. The traveling carriage E E E E, constructed and operated in the manner and for the purpose set forth.
2. The double rack *g g* and the pinion *f* on the apron-roll *j*, or their equivalents, for traversing the roll *j* across the main apron C in the manner and for the purpose set forth.

THOS. B. BUTLER.

In presence of—

JOHN A. WEED,
EDWD. P. WEED.
